UNITED STATES PATENT OFFICE.

CARL FRITZ SJÖMAN AND CARL GUSTAF PETTERSSON, OF STOCKHOLM, SWEDEN, AS
SIGNORS TO J. & C. G. BOLINDERS MEKANISKA VERKSTADS AKTIEBOLAG, OF
STOCKHOLM, SWEDEN, A CORPORATION.

REVERSING MEANS FOR INTERNAL-COMBUSTION MOTORS.

Application filed June 17, 1924, Serial No. 720,681, and in Sweden June 23, 1923.

The present invention refers to a device for reversing internal combustion motors with the aid of so-called premature ignition.

The invention is principally characterized by the fuel pump or its piston being adjustable relatively to the part of the motor actuating the pump piston, in such manner that the injection will, by reason of the adjustment, take place earlier than under normal 10 conditions so as to bring about the premature ignition required for the reversal. The pump or pump piston thus adapted to be reversed is connected with a device so arranged as to retain the pump or the pump 15 piston in the reversed position, while releasing the said pump or piston and bringing it back to the normal position through the action of the preceding pump stroke.

An embodiment of the invention is disclosed in the accompanying drawing, the piston of the fuel pump being adjustable in the manner set forth. Both figures in the drawing show the device in a vertical longitudinal section. Fig. 1 shows the device 25 adjusted for normal operation, and Fig. 2 the same adjusted for reversal of the motor.

Attached in the fixed frame 1 is the pump cylinder 2, in which the pump piston 3 is movable to and fro, and is actuated in 30 known manner by a governor weight 5 adapted to reciprocate on a stepped surface 4. Arranged in the rear part of the pump cylinder 2 is a plunger 6 adapted to be displaced in the path of the pump piston 3, 35 said plunger being attached with its outer end in the cross piece 7 adapted to be guided in a fixed part 9 of the frame 1 by means of a threaded spindle 8 attached to the said cross piece. A nut 10 is adapted to be 40 screwed on the outer end of the spindle 8. The cross piece 7 is movably connected, by means of link rods 11 (one on either side of the pump cylinder) to a sleeve 12 adapted to be reciprocated on the front portion of 45 the pump cylinder, the fore part of the said sleeve forming a guide for the pump piston 3. The latter abuts with a boss 13 forwards against the bottom of the sleeve 12 under the influence of the spring 14 inserted be- 50 tween the bottom of the pump cylinder 2 and a part 15 attached to the inner end of the pump piston 3. Pivotaly connected with the sleeve 12 by means of a pin 16 is a lever 17 having on the front side a hook-like pro-

jection 18 which, when the lever is turned 55 forwards (toward the left in the drawing), may be brought into engagement with a fixed hook-like projection 19 shaped in a corresponding manner. Inserted between lever 17 and the frame 1 is a spring 20 tending 60 to turn the lever rearwards. The stepped surface 4 is slidably arranged on a fixed part 21, and is movably connected with the sleeve 12 by means of links 22. 23 is the suction pipe of the pump and 24 the pressure pipe. 65 25 is an abutment affording a support for the lever 17, when the latter is swung forwards.

When the motor is to be reversed, the lever 17 is turned forwards, that is to say towards 70 the left, the hook-like projection 18 of the lever being then brought below the projection 19. The lever is now abutting against the fixed part 25, and on a continued movement of the lever towards the left the projection 18 will be brought under the part 19. At the same time the guide sleeve 12 is pushed forwards, and the pump piston is 75 carried with it under the action of the spring 14. When moved forwards the sleeve 12 also 80 brings the cross piece 7 and the plunger 6 with it by means of the link rods 11. The parts then occupy the position shown in Fig. 2 and are retained therein by the mutual engagement of the parts 18 and 19. Thus the 85 pump piston 3 has been approached with its fore end to the governor weight 5 which, when moving forwards, hits the piston 90 earlier than under normal conditions, an earlier injection and, consequently, premature ignition being caused thereby, so that the motor is reversed. The length of the 95 pump stroke, that is to say the quantity of the fuel introduced on the previous injection, remains the same as normally, and corresponds to the distance 26 between the inner end of the pump piston 3 and the inner end of the plunger 6, which distance remains 100 constant notwithstanding the said forward movement of the parts. On account of the plunger 6 having been brought into the advanced position shown in Fig. 2, it will be 105 hit by the inwardly moving pump piston, and is thus displaced backwards. This movement is imparted to the cross piece 7 which pulls the sleeve 12 backwards by means of the link rods 11, whereby the pump piston 3 is brought backwards so as to re-

assume its normal position. The lever 17 also follows backwards, its hook-like projection 18 being then disengaged from the hook 19. After the lever has thus been released, it will be turned back by the spring 20, so that the projection 18 is elevated in front of the hook 19 and abuts against the latter so as to retain the parts in the position of normal running.

10. The arrangement may evidently be modified with respect to the details thereof, without departing from the principle of the invention. Thus, in place of the lever 17, some other means may be used to move the 15 pump piston, for instance a spring acting on the pump piston, such spring being so arranged as to be brought into operation as soon as the piston has become free for being displaced forwards by the lowering of the 20 part 18.

What we claim as new and desire to secure by Letters Patent of the United States of America is:

1. In combination, an inertia tappet adapted to be constantly operated by an internal combustion engine during working of the latter, a fuel pump for the engine constantly operated by the tappet during working of the engine and comprising a piston member and a cylinder member, means for adjusting one of said members relatively to the tappet to cause the actuator to operate the adjusted member earlier than under normal conditions, so as to bring about the premature ignition required for the reversal of the engine and means connected to said cylinder for causing the effective stroke of the piston to remain constant.

2. A combination as claimed in claim 1 including mechanism for latching said adjusting means to retain the adjustable member of the pump in the position for reversing, and other mechanism actuated by the pump for releasing said adjustable member to permit the latter to return to normal position through the action of the preceding pump stroke.

3. In combination, an inertia tappet adapted to be constantly operated by an internal combustion engine during working of the latter, a fuel pump for the engine constantly operated by the tappet during working of the engine and comprising a cylinder and a piston, manually operated means for ad-

justing the pump piston toward the tappet, 55 whereby the injection will take place earlier than under normal conditions, so as to bring about the premature ignition required for the reversal of the engine and means connected to said cylinder for causing the effective stroke of the piston to remain constant.

4. In combination, an inertia tappet adapted to be constantly operated by an internal combustion engine during working of the latter, a fuel pump for the engine constantly operated by the tappet during the working of the engine and comprising a piston and a cylinder, manually operated means for moving said piston toward the tappet to 70 permit the tappet to actuate the piston earlier than under normal conditions so as to bring about earlier injection of the fuel and the premature ignition required for the reversal of the engine, a spring bearing on 75 said piston for constantly forcing the same toward the tappet, a stem cooperating with the piston for limiting the effective stroke of the piston during normal running as well as during reversal, and connecting elements joining said manually operated means to the stem whereby the stem is adjusted each time the manually operated means is operated.

5. In combination, an inertia tappet adapted to be constantly operated by an internal combustion engine during working of the latter, a fuel pump for the engine comprising a cylinder and a piston, a spring for forcing the piston toward said tappet into a position where it will be always actuated by the tappet during running of the engine, a stem cooperating with the piston for limiting the effective stroke of the piston, links connected to the stem, a lever connected to the links, a spring for swinging the lever in one direction, a stationary abutment, an abutment on the lever adapted to cooperate with the stationary abutment for latching the lever in a set position, a sleeve actuated by the lever, and a cam moved by the sleeve and engaging the tappet for controlling the latter.

In testimony whereof we affix our signatures.

CARL FRITZ SJÖMAN.
